UNITED STATES PATENT OFFICE.

HUBBARD F. WEEKS, OF FREEHOLD, NEW JERSEY.

DESIGN FOR AN AXLE-CENTER AND FIFTH-WHEEL PLATE.

SPECIFICATION forming part of Design No. 35,589, dated January 14, 1902.

Application filed October 14, 1901. Serial No. 78,662. Term of patent 14 years.

To all whom it may concern:

Be it known that I, HUBBARD F. WEEKS, a citizen of the United States, residing at Freehold, in the county of Monmouth and State of New Jersey, have invented and produced a new and original Design for an Axle-Center and Fifth-Wheel Plate; and I do declare the following to be a full, clear, and exact description of the same, reference being had to the accompanying drawing, forming a part thereof.

The figure shows in perspective a view of my new design.

As shown by the drawing, the leading or characteristic features of my design consist in a plain straight body portion, constituting an axle-center, and a semicircular-shaped portion or curved plate disposed mainly on one side of the body portion and in a horizontal plane above the parallel horizontal plane of the top of the axle-center, the ends of the plate projecting slightly beyond the said axle-center and lying adjacent the ends of the axle-center.

The letter A designates the body portion or axle-center, which is plain and straight in shape, and B represents the ends of the same.

C is a plate of a semicircular shape located in a horizontal plane slightly above the parallel horizontal plane at the top surface of the axle-center or body portion.

D D are the free ends of the semicircular plate, which project beyond the line of the axle-center, the major portion of the semicircular plate being at one side of the body portion or axle-center.

35

E is the flat upper surface of the plate, and F is an area bounded by the plate and body portion.

The complete design appears to the eye as a structure having a straight body portion with a semicircular plate disposed at one side of a straight line passing longitudinally through the said body portion and said plate being located above the top surface of the axle-center and having free ends projecting beyond the perpendicular face of the said center.

40 Having described my invention, what I claim as new, and desire to secure by Letters Patent, is—

45 The design for an axle-center and fifth-wheel plate, as shown, and with the characteristic features described.

50 In testimony whereof I affix my signature in presence of two witnesses.

HUBBARD F. WEEKS.
